WIRELESS RECEIVING SYSTEM

James Robinson, London, England

Application November 2, 1934, Serial No. 751,205
In Great Britain November 7, 1933

9 Claims. (Cl. 250—20)

This invention is for improvements in or relating to wireless receiving systems and the primary object of the invention is to provide a high degree of selectivity in reception more especially for the reduction of heterodyne interference produced by the interaction between the carrier wave of the wanted signals and the carrier waves of the other signals. By this invention use is made of the conditions of normal modulated carrier wave transmission wherein the transmission frequencies arrive at a receiving system in their normal phase relationship. By the expression "modulated carrier wave transmission" I mean a carrier wave which is interrupted or altered in any manner according to the intelligence to be transmitted and I include transmissions in which the carrier component is partially or completely suppressed at the transmitter such as single side band systems and is reinstated at the receiver by a local oscillator or is built up by means of a receiver of low damping.

According to the invention the method of receiving modulated carrier wave transmissions comprises producing a plurality of wave path differences as between the wanted transmission and an interfering transmission of such relative frequency as to cause a heterodyne beat interference, receiving a plurality of portions of the wanted and interfering signals in different phase relationships resulting from the said path differences of the transmissions and combining these portions of the signals in the accumulative sense for the wanted signals whereby the heterodyne beat effect is diminished due to the different phase relationships which consequently occur between the received portions of the interfering signals.

The invention also comprises the method of receiving modulated carrier wave transmissions which comprises receiving on a plurality of spaced aerials both a wanted signal and an interfering signal arriving from a different direction and producing a heterodyne interference, and combining all the received signals at a single receiver whereby the wanted signals are cumulated but the phase-differences of the various heterodyne beats at the different aerials causes their total effect to be diminished.

The invention further comprises a receiving system for modulated carrier wave transmissions comprising a plurality of aerials spaced apart, selective receiving means of such high order of selectivity as to remove direct interference of unwanted transmissions from the signals received, means combining the modulation signals comprising the wanted signals and heterodyne beat

interference signals obtained from the aerials in approximately the same phase for the wanted signals whereby the heterodyne beat interference signals are combined in out-of phase relationship and with diminished resultant effect. In one form there is provided means (i. e. comprising a rectifier) at each aerial for detecting the modulation signals and means for transferring the received signals to a receiver common to all the aerials for combining the received signals.

Wanted and unwanted signals arriving from different directions at one of the aerials aforesaid and closely adjacent as regards their carrier frequencies produce an undesired heterodyne beat effect. The same signals arriving at another of the aerials also produce the same heterodyne beat note, but there will be a phase difference between the heterodyne notes produced in the two aerials due to the difference in path distance between the aerials for the wanted and the unwanted signals. Thus by combining the signals collected at the several aerials the wanted signals may be combined sensibly arithmetically, whereas the interfering or heterodyne beat effects are combined vectorially with the result that the latter interference is minimized and may for all practical purposes be eliminated. The aerials of which there may be two or preferably more than two may be spaced in any desired manner and for example may be arranged in a straight line with uniform spacing or in a circle.

According to a feature of the invention the signal-accepting means at each of the aerials comprises a frequency converting device for changing the frequency of the carrier-wave to another frequency for the transfer of the signals to the major receiving means common to all the aerials. The transfer of the signals from the signal-accepting means at each aerial to the major receiving means may be effected by means of lines or by means of wireless links using, for example, a supersonic carrier-frequency for this purpose.

Preferably and more especially where the aerials are spaced considerable distances apart means is provided, for example in each of the connections between the aerials and the major receiving apparatus, for the relative adjustment of the phase of the signals for the purpose of bringing the wanted signals arriving from each of the aerials into phase agreement. Furthermore the phase adjusting means may be employed to effect a combination of the wanted signals which is not truly arithmetical, in order to reduce still further a heterodyne interference resulting,

for instance from wanted and unwanted signals arriving from closely similar directions.

The invention will further be described with reference to the accompanying drawings in which Figures 1, 2 and 3 show diagrammatically alternative systems for carrying out the invention.

In the drawings four aerials 10, 11, 12 and 13 are provided spaced any distance apart (e. g. by a distance of the order of a wavelength of the signals to be received) and in any symmetrical or unsymmetrical arrangement. These aerials may either be non-directional or may be constructed in any known manner to have directional characteristics for the purpose hereinafter described or again they may each be of the multiple type to minimize the effects of fading. At each aerial there is provided a signal accepting means 14 of any well known form and including in this instance a detector or other equivalent means for isolating the modulation frequencies. The modulation signal output from each of the receivers 14 is conducted by lines 15 to a main receiving station generally indicated at 16. The lines 15 are connected through phase adjusting means 17 for each receiver to a main receiving apparatus indicated at 18 in which the signals received at the several aerials are combined. The receivers 14 are highly selective for the purpose of eliminating interference as far as is possible and may be such as are described in U. S. Patent No. 1,821,032, dated 1st September, 1931, in order to obtain substantial freedom from interference due to direct reception of the modulation signals of unwanted transmissions.

Thus the selectivity of the receivers 14 may be such that there is no response to interfering signals whereof the carrier frequency lies outside the response curve of the receiver but differs from the frequency of the wanted carrier wave by an amount less than the highest modulation frequency of the wanted signal. Such a receiver embodies means for correcting the inherent signal distortion due to the high selectivity of the receiver in order that modulations of the carrier wave of the wanted signal corresponding to its whole modulation range may be faithfully reproduced. Alternatively, the receivers may be described as having such high selectivity and/or low damping that there is no response to interfering modulated signals whereof the side band frequencies differ from the frequency of the wanted carrier wave by an amount less than the highest modulation frequency of the wanted signal, modulations of the carrier wave of the wanted signal corresponding to its whole modulation range being faithfully reproduced by the aid of means for correcting the inherent signal distortion due to the high selectivity of the receiver.

It will be understood that the phrase "highest modulation frequency" is employed to refer to the highest modulation frequency that is considered necessary for the tolerably good or satisfactory reproduction of the signals, as distinct from such higher frequencies as may be present but of which the absence from the received signal is not noticeable. The phrase "no response" is employed to indicate that the interference from a normally modulated transmission is negligibly small to a normal individual when the wanted and the interfering signals are of comparable field strength.

It can be shown that it is a characteristic of receivers of such high degree of selectivity that the amplitude of the signal response is inversely proportional to the frequency of the signal mod-

ulation. It is of course necessary to subsequently correct for such distortion.

In operation assuming that the wave front of signals required to be received is moving in the direction indicated by the arrows 20 and that of the interfering signals in the direction indicated by the arrows 21 and for the purpose of explanation that the frequencies of the two transmissions are such that carrier-waves of the two transmissions heterodyne to produce in a receiver an audible beat note which is objectionable. Under these circumstances each of the receivers 14 which are tuned to select the required signals will also produce beat note interference.

Further assuming that at the aerial 11 the relative phase of the carrier wave of the wanted transmission with respect to that of the unwanted transmission is such as to produce a heterodyne peak at a given instance. Then at the other aerials the phase relationship of the two transmissions will be different depending in this instance solely upon the difference in path of the unwanted and wanted signals. For instance at the aerial 10 the difference in phase will depend upon the distance apart of the aerial 10 from the aerial 11. The wanted signals arrive at the aerials 10 and 11 simultaneously but the unwanted signals arrive on the two aerials in succession so that if the distance apart of these aerials is for instance half a wavelength of the unwanted signals the resultant beat note produced will be in phase opposition to the beat note received from the aerial 11. The phase relationship of the heterodyne beat note received in the separate receivers will differ as between one receiver and another depending on the distribution of the aerials for any given transmissions so that by combining the received signals at a central receiver the heterodyne beat note is suppressed to a large degree. By combining the received signals at the central receiver the wanted signals are added together arithmetically or substantially arithmetically because the phase difference between the modulation signals from the several aerial receivers 14 will be negligibly small except for a very wide spacing of the aerials and in this latter case the wanted signals may be brought into phase agreement by slight adjustments of the phase correcting devices 17. The heterodyne beat notes will be considerably different in phase and will thus be combined vectorially so that the resultant is zero or some relatively small value.

In an alternative arrangement the signal accepting means indicated at 14 for each aerial may comprise for instance a high frequency amplifier to pass on the high frequency signals to the central receiving station 16 and in this case detection of the signals from each aerial takes place in the main receiver before the signals are combined, for instance in the phase controlling devices 17. In this arrangement it is important that the paths between the aerials and the main receiver should be the same or alternatively the phase adjusting devices 17 should be adjusted to compensate for any differences. In the arrangement previously described with reference to Figure 1, in which the modulation signals are transferred from the aerials to the central receiver it is not so essential to control the phase of the signals before they are combined because unless the spacing of the aerials is very large the effect upon the phase of the modulation signals is very small.

In the case of single side band transmissions the carrier may be supplied by means of a locally

produced carrier frequency applied to the signals at each of the receiving devices 14, or if a small percentage of carrier is included in the transmitted signals, the receiving devices 14 may be of such low damping as to build up this carrier component to the normal value for the received signals.

It will be understood that this suppression of the heterodyne beat note or a plurality of such notes in the case of two or more interfering stations is obtained to a more or less complete extent depending upon the angle at which the transmissions arrive and the number of aerials and provided the direction of the unwanted transmission does not exactly coincide with that of the wanted transmission.

In order further to ensure freedom from heterodyne interference each of the aerials 10, 11, 12 and 13 may be constructed in any known manner to have pronounced directional characteristics so arranged as to provide a small response for an unwanted transmission as compared with the response for the wanted transmission. Each aerial may thus consist of a plurality of frame or loop aerials adjustable as a unit according to the direction of reception required and suitable means may be employed for this adjustment of the aerials simultaneously by a remote control operable at the central receiving station.

Such a system is shown diagrammatically in Figure 3 in which a plurality of loop aerials 40 are provided spaced apart as in the preceding example. At each of these loop aerials 40 there is provided, in this instance, a filter 41 such as that described in U. S. Patent No. 1,898,895, for suppressing one side band of the received signals, and signal accepting means 42 including a detector for isolating the modulating frequencies. The modulation signal output of each device 42 is conducted by lines to a main receiving apparatus 44 common to all the aerials through phase adjusting means 43. In construction the signal accepting means 42 constitute highly selective receivers for eliminating, as far as is possible, direct interference due to an unwanted transmission, and such highly selective receiving apparatus may be of the form described in the aforementioned Patent No. 1,821,032. The loop aerials 40 are adjustable as regards direction in order to provide the best response from wanted signals arriving in the direction indicated by the arrows 20, and a lesser response from the unwanted signals arriving in the direction indicated by the arrows 21. The loop aerials 40 are controlled by means of a remote control device 45 located at the main receiver and connected by lines indicated at 46 to the several loop aerials.

In the embodiment of the invention shown in Figure 2 of the drawings each of a plurality of spaced aerials 30 feeds signal selecting means 31 which may have high selectivity for the required signals and the output of the signal selecting means 31 is applied to frequency changing means 32 in which the modulation signals are impressed upon a carrier wave of a frequency different from that of the original carrier wave. The modulated carrier wave output from the device 32 is then applied to a filter 33 for suppressing one side band of the signals and the remaining side band and the local carrier wave is transmitted through a channel indicated at 34 to the central receiving station generally indicated at 35. The channel 34 for each aerial may consist of a conducting line as described with reference to Figure 1 or may be constituted by a wireless link connect-

ing the receiving station at each aerial with the central receiving station 35.

The suppression of one side band of the received signals at the device 33 serves further to reduce any possible heterodyne interference by eliminating any interfering frequency occurring in the suppressed side band.

The central receiving station 35 comprises a highly selective receiving means 36 for the signals from each aerial. This receiving means being for example of the kind described in U. S. Patent No. 1,821,032, dated 1st September, 1931 and comprising essentially a rectifier for isolating the modulation signals. The modulation signals from each of the devices 36 are passed through 15 a phase adjusting means 37 to a single amplifier 38 in which the modulation signals from the several aerials are combined in the manner hereinbefore described with reference to Figure 1 and thus provide an output at 39 free from interference.

Instead of combining the signals from the several aerials so that the wanted signals are added together arithmetically the phase adjusting devices 17 in Figure 1 or 37 in Figure 2 may be so 25 adjusted as to bring the heterodyne interference from the several aerials in phase and in this case the wanted signals from the several aerials will be added vectorially and will balance out. The heterodyne interference thus obtained may then 30 be opposed to complete signals received on a separate receiving system to suppress the unwanted heterodyne in these signals. Alternatively, the heterodyne interference isolated as above described may be opposed to the output thus obtained 35 from the amplifier 19 in Figure 1, or 39 in Figure 2, to eliminate any residual heterodyne interference which may be present.

It will be understood that in all cases the plurality of spaced aerials provides for relative path 40 distances of the wanted and interfering signals, which differ as between one aerial and another so that by the combination of the signals preferably after detection and in an arithmetical sense for the wanted signals the heterodyne beat effects will be added vectorially and thus tend to 45 balance out.

Also the same system of aerials may be used to receive a plurality of transmissions simultaneously with the advantage of the reduction of 50 heterodyne interference in the reception of each of the transmissions.

I claim:

1. A receiving system for modulating carrier wave transmissions comprising the combination of an aerial, selective receiving means at said aerial tuned for the wanted signals, the selectivity of said receiving means being such that there is no response to interfering modulation signals whereof the carrier frequency differs from the frequency of the wanted carrier wave by an amount less than the highest modulation frequency of the wanted signal, at least one additional aerial spaced apart from the first said aerial and also having selected receiving means similarly tuned for the wanted signals and of such high order of selectivity as to remove modulation interference of the unwanted transmission, said additional aerial being so spaced from the first said aerial that the heterodyne beat note produced by the wanted and unwanted signals is different in phase at the two aerials, each of said aerials having pronounced directional characteristics, and means combining the modulation signals comprising the wanted signals and 75

the heterodyne beat interference signals in approximately the same phase for the wanted signals whereby the heterodyne beat interference signals are combined in out-of-phase relationship and with diminished effect.

5 2. A receiving system for modulating carrier wave transmissions comprising the combination of an aerial, selective receiving means at said aerial tuned for the wanted signals and of such aerial high order of selectivity as to remove modulation interference of an unwanted transmission, at least one additional aerial spaced apart from the first said aerial and also having selected receiving means similarly tuned for the wanted signals and of such high order of selectivity as to remove modulation interference of the unwanted transmission, said additional aerial being so spaced from the first said aerial that the heterodyne beat note produced by the wanted and unwanted signals is different in phase at the two aerials, means to suppress one side band of the signals received at each aerial, and means combining the modulation signals comprising the wanted signals and the heterodyne beat interference signals in approximately the same phase for the wanted signals whereby the heterodyne beat interference signals are combined in out-of-phase relationship and with diminished effect.

3. A wireless receiving system for modulated carrier wave transmissions comprising several directional aerials indiscriminately spaced apart, selective receiving means at each aerial similarly tuned for the wanted signals and of such high order of selectivity as to remove modulation interference of the unwanted transmissions, means to suppress one side band of the signals received at each aerial, means combining the modulation signals comprising the wanted signals and the heterodyne beat interference signals obtained from the aerials in approximately the same phase for the wanted signals, whereby the heterodyne beat interference signals are combined in out-of-phase relationship and with diminished resultant effect.

4. A receiving system for modulating carrier wave transmissions comprising the combination of an aerial, selective receiving means at said aerial tuned for the wanted signals, the selectivity of said receiving means being such that there is no response to interfering modulation signals whereof the carrier frequency differs from the frequency of the wanted carrier wave by an amount less than the highest modulation frequency of the wanted signal, at least one additional aerial spaced apart from the first said aerial and also having selective receiving means similarly tuned for the wanted signals and of such high order of selectivity as to remove modulation interference of the unwanted transmission, said additional aerial being so spaced from the first said aerial that the heterodyne beat note produced by the wanted and unwanted signals is different in phase at the two aerials, a receiving station common to the aerials, a frequency converting device at each aerial for changing the frequency of the carrier-wave to another frequency for transfer of the signals to said receiving station, and means at said receiving station combining the modulation signals comprising the wanted signals and the heterodyne beat interference signals in approximately the same phase for the wanted signals whereby the heterodyne beat interference signals are combined in out-of-phase relationship and with diminished effect.

75 5. A receiving system for modulated carrier

wave transmissions comprising the combination of an aerial, selective receiving means at said aerial tuned for the wanted signals, the selectivity of said receiving means being such that there is no response to interfering modulation signals whereof the carrier frequency lies outside the response curve of the receiver but differs from the frequency of the wanted carrier wave by an amount less than the highest modulation frequency of the wanted signal, at least one additional aerial spaced apart from the first said aerial and also having selective receiving means similarly tuned for the wanted signals and of similar high order of selectivity, said additional aerial being so spaced from the first said aerial that the heterodyne beat note produced by the wanted and unwanted signals is different in phase at the two aerials, and means combining the modulation signals comprising the wanted signals and the heterodyne beat interference signals in approximately the same phase for the wanted signals, whereby the heterodyne beat interference signals are combined in out-of-phase relationship and with diminished effect.

6. A wireless receiving system for modulated carrier wave transmissions comprising several aerials so spaced with regard to the direction and wave-length of wanted signals and unwanted signals that heterodyne beat effects between wanted and unwanted signals are in different phase at at least two of the aerials, selective receiving means at each aerial similarly tuned for the wanted signals, the selectivity of said receiving means being such that the amplitude of the modulation frequencies of the wanted signals throughout the whole of the modulation frequency range is relatively altered, said receiving means including devices for relatively altering the amplitude of the modulation frequencies in the opposite sense, and means combining the modulation signals comprising the wanted signals and the heterodyne beat interference signals obtained from the aerials in approximately the same phase for the wanted signals, whereby the heterodyne beat interference signals are combined in out-of-phase relationship and with diminished resultant effect.

7. A wireless receiving system for modulated carrier wave transmissions comprising a plurality of aerials disposed in spaced relation, and means whereby wanted modulation signals intercepted by said aerials are combined in approximately the same phase and are reproduced while heterodyne beat notes between wanted and unwanted signals intercepted by said aerials are combined in different phase and substantially eliminated, said last named means including selective receiving means for the signals from said aerials, the selectivity of said receiving means being such that there is no response to interfering modulation signals whereof the carrier frequency of such interfering signal differs from the carrier frequency of the wanted signal by an amount less than the sum of the highest modulation frequencies of both signals.

8. A wireless receiving system for modulated carrier wave transmissions comprising a plurality of aerials disposed in uniformly spaced relation, and means whereby wanted modulation signals intercepted by said aerials are combined in approximately the same phase and are reproduced while heterodyne beat notes between wanted and unwanted signals intercepted by said aerials are combined in different phase and substantially eliminated, said last named means including se-

lective receiving means for the signals from said aerials, the selectivity of said receiving means being such that there is no response to interfering modulation signals whereof the carrier frequency of such interfering signal differs from the carrier frequency of the wanted signal by an amount less than the sum of the highest modulation frequencies of both signals.

9. A wireless receiving system for modulated carrier wave transmissions comprising several aerials disposed in uniformly spaced relation in a straight line, selective receiving means at each aerial similarly tuned for the wanted signals, the selectivity of said receiving means being such

that there is no response to interfering modulation signals whereof the carrier frequency differs from the frequency of the wanted carrier wave by an amount less than the highest modulation frequency of the wanted signal, and means combining the modulation signals comprising the wanted signals and the heterodyne beat interference signals obtained from the aerials in approximately the same phase for the wanted signals, whereby the heterodyne beat interference signals are combined in out-of-phase relationship and with diminished resultant effect.

JAMES ROBINSON.
